(57) **CLAIM**

The ornamental design for a portable water pumping station,
as shown and described.

DESCRIPTION

FIG. 1 is an isometric view of an embodiment of a portable
water pumping station;

FIG. 2 is a front-view of the embodiment of the portable water
pumping station in FIG. 1;

FIG. 3 is a top-view of the embodiment of the portable water
pumping station in FIG. 1;

FIG. 4 is a side-view of the embodiment of the portable water
pumping station in FIG. 1;

FIG. 5 is a back-view of the embodiment of the portable water
pumping station in FIG. 1; and,

FIG. 6 is a bottom-view of the embodiment of the portable
water pumping station in FIG. 1.
